UNITED STATES PATENT OFFICE

VANDER B. LOWDER, OF CONCORD, NORTH CAROLINA

AUTOMATIC STOP FOR ELECTRICALLY-DRIVEN MACHINES

Application filed October 22, 1929. Serial No. 401,592.

This invention relates to automatic stop systems for electrically driven machines, and more particularly for cloth finishing machines and the like, such for example as disclosed in my prior Patent No. 1,703,774, dated February 26, 1929.

One object of the invention is to provide simple and efficient means for opening the main switch supplying current to the motor 10 in the event that holes, defects, or loose ends are encountered in the cloth passing through the machine.

As industrial motors are usually operated by current of relatively high voltage, and as 15 it is undesirable to employ such voltage on the feeler device for controlling the automatic stop mechanism, another object of the invention is to provide a transformer arrangement for stepping down the voltage to 20 the desired extent, and to utilize such reduced voltage for operating a relay.

In connection with automatic stop systems of this general character it is frequently desirable to be able to manually start and stop 25 the motor at will independent of the automatic stop device. Still another object of the invention therefore is to combine with the above mentioned transformer and relay manually operated mechanism in the form 30 of start and stop push buttons for opening and closing the main switch controlling the supply of current to the motor.

In order that the invention may be readily understood, reference is had to the accompanying drawing forming part of this specification and in which the single figure is a diagram showing the circuit connections which I prefer to employ and conventionally 35 illustrating the apparatus which is associated therewith.

Referring to the drawings in detail, 1 designates an electric motor connected in any suitable way to a cloth finishing or similar 45 machine for driving the same. This motor may be of any suitable type, but as illustrated, it is shown as a three-phase alternating current motor fed from a supply circuit 2 in which is interposed a three-pole switch 3. 50 This switch is biased to open position, a

spring 4 being shown, tending to open the switch.

The switch is arranged to be closed and held closed by electromagnetic means, illustrated as an electromagnet 5 mounted adjacent the switch and included in a control circuit 6, 7, the conductor 6 tapping the supply circuit at the point *a*, outside of the switch, and the conductor 7 extending to the push button switches hereinafter described. Additional control conductors 8 and 9, tapping the supply circuit at the points *b* and *c*, outside and inside of the main switch, respectively, are provided. The conductor 8 is connected to one side of the primary winding 65 of a transformer 10, the other side of this winding being connected by a conductor 11 to a contact 12 engaged by the armature 13 of a relay, pivoted at 13^a, and normally held against the contact by means of a spring 13^b. 70 This armature is shown as U-shaped, one leg engaging the contact 12 as described, and the other leg engaging a similar contact 12'. From this extends a conductor 14 to a contact point 15 forming part of one of the push 75 button switches. A similar contact 16 forming part of the other push button switch is connected to the control conductor 9.

The push button switches comprise independently movable switch members 17 and 18, pivoted at 19 and 20 respectively. Push buttons 21 and 22 are shown as adapted to bear against and operate the respective switch members. A spring 23 normally holds the switch member 17 in engagement with the 85 contact 15, and a similar spring 24 normally holds the switch member 18 out of engagement with the contact 16, as shown in the drawing.

The conductor 7, which is connected at one 90 end to the electromagnet 5, is connected at the other end to a conductor 25 which is united to pivot points 19 and 20 of the two switch members 17 and 18.

The above mentioned relay has a winding 95 26 disposed adjacent the armature 13 and one end of this winding is connected by a conductor 27 to one side of the secondary winding of the transformer 10. The other end of the relay winding 26 is connected by con- 100

ductor 28 to one member 29 of the feeler device, and the other member 31 of which is connected by means of a conductor 30 with the other side of the secondary winding of the transformer.

5 Pivots secured to the member 31 are gravity operated feeler fingers 32 between which and the member 29 the cloth passes, such cloth being indicated in dotted lines at 10 X. This feeler device in its entirety is or may be similar to that shown in my prior patent above identified or in my copending application Serial No. 395,393, filed September 26, 1929.

15 When it is desired to start the motor, the push button 22 is depressed, thus closing a circuit at the point 16, 18 between the conductors 7 and 9. Current then flows from the supply circuit 2 over conductor 6, through the electromagnet 5 and conductors 20 7 and 9 back to the other side of the supply circuit, thus energizing the magnet 5 and causing it to close the main switch. As soon as this switch is closed another circuit is established from the point c through the conductor 8, the primary of the transformer 10, conductor 11, contacts 12 and 12' and the armature 13, conductor 14 and contact 15, switch member 17 and the conductors 7 and 30 6, through the electromagnet 5, this circuit being normally closed and serving to maintain the energization of the electromagnet 5 after the circuit opens at the point 16, 18. Thus when the push button 22 is momentarily 35 depressed and then released, the main switch 3 is closed by the magnet 5 and subsequently maintained closed by means of a holding circuit including the conductor 8, the relay contacts, and the switch member 17. When, 40 therefore, it is desired to stop the motor, it is only necessary to depress push button 21, thus interrupting this holding circuit at the point 15, 17. This de-energizes the magnet 5 and the spring 4 opens the main switch.

45 As long as the cloth passing through the feeler device is free from defects, such cloth serves to insulate the feeler fingers 32 from the member 29, and thus the circuit through the relay winding 26 is normally open.

50 When, however, any hole or loose end passes under any of the feeler fingers 32, the circuit through the relay winding is automatically closed, current being supplied from the secondary of the transformer 10. The armature 13 is thus pulled over, thereby interrupting the holding circuit at the points 12, 12', and the main switch opened.

55 It will thus be seen that the holding circuit includes the primary winding of the transformer, the contacts of the relay and a normally closed push button switch, and that I have provided another push button switch controlling a wholly independent circuit by means of which the main switch may be 60 closed after it has been opened. It will

further be noted that while the relay contacts are in series with the primary of the transformer, the relay winding is in circuit with the secondary thereof, and it is thought that the many advantages of my exceptionally simple and effective combined automatic and manual control system will be readily appreciated by those skilled in the art. 70

What I claim is:

1. In an automatic stop system for electrically driven machines, the combination with an electric motor and supply circuit therefor, of a switch in said circuit biased to open position, electromagnetic means for holding said switch closed, a circuit including a relay for normally maintaining said electromagnetic means energized and said switch closed, and automatic means responsive to abnormal conditions for causing said relay to interrupt said last mentioned circuit and thus permit said switch to open. 75

2. In an automatic stop system for electrically driven machines, the combination with an electric motor and supply circuit therefor, of a switch in said circuit biased to open position, electromagnetic means for closing said switch and holding it closed, a normally closed circuit, including a relay, for maintaining said electromagnetic means energized and said switch closed, automatic means responsive to abnormal conditions for causing said relay to interrupt said normally closed circuit, and manual means, independent of said relay, for restoring the circuit through said electromagnetic means. 80 90

3. In an automatic stop system for electrically driven machines, the combination with an electric motor and supply circuit therefor, of a switch in said circuit biased to open position, electromagnetic means for closing said switch and holding it closed, a normally closed circuit for maintaining said electromagnetic means energized and said switch closed, automatic means responsive to abnormal conditions for interrupting said normally closed circuit, additional means for opening said circuit at will, and manual means, independent of said automatic means, for restoring the circuit through said electromagnetic means. 105 110

4. In an automatic stop system for electrically driven cloth finishing machines and the like, the combination with an alternating current motor and a supply circuit therefor, of a switch in said circuit biased to open position, electromagnetic means for closing said switch and holding it closed, a feeler device through which the cloth passes, a transformer, a circuit connecting said feeler device with the secondary of said transformer, a relay having a winding included in said secondary circuit, and having contacts controlled by said winding, and a normally closed circuit tapping said supply circuit and including in series said electromagnetic 120 125 130

means, the primary of said transformer and the contacts of said relay.

5. In an automatic stop system for electrically driven cloth finishing machines and the like, the combination with an alternating current motor and a supply circuit therefor, of a switch in said circuit biased to open position, electromagnetic means for closing said switch and holding it closed, a feeler device through which the cloth passes, a transformer, a circuit connecting said feeler device with the secondary of said transformer, a relay having a winding included in said secondary circuit, and having contacts controlled by said winding, a normally closed circuit tapping said supply circuit and including in series said electromagnetic means, the primary of said transformer, and the contacts of said relay, and a manually operated switch also in said normally closed circuit.

In testimony whereof I affix my signature.
